US0D1044754S

(12) **United States Design Patent** (10) Patent No.: **US D1,044,754 S**
(45) Date of Patent: ** Oct. 1, 2024

(54) **MAGNETIC BASE**

(71) Applicant: **WEIHAI FUNWATER OUTDOOR CO., LTD**, Weihai (CN)

(72) Inventors: **Shengwei Liang**, Weihai (CN); **Zeguang Xiao**, Weihai (CN); **Xiaoye Xin**, Weihai (CN)

(73) Assignee: **WEIHAI FUNWATER OUTDOOR CO., LTD**, Weihai (CN)

(**) Term: **15 Years**

(21) Appl. No.: **29/852,005**

(22) Filed: **Sep. 2, 2022**

(30) **Foreign Application Priority Data**

Jul. 27, 2022 (CN) 202230482236.9

(57) **CLAIM**

The ornamental design for a magnetic base, as shown and described.

DESCRIPTION

FIG. 1 is a perspective view of a magnetic base showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the magnetic base that form no part of the claimed design.

1 Claim, 8 Drawing Sheets
